US0D1104634S

(12) United States Design Patent (10) Patent No.: US D1,104,634 S
(45) Date of Patent:  Dec. 9, 2025

(54) BOWL

(71) Applicant: YETI Coolers, LLC, Austin, TX (US)

(72) Inventors: Kyle Ellison, Austin, TX (US); Dustin Bullock, Austin, TX (US); Colin Darling, Austin, TX (US)

(73) Assignee: YETI Coolers, LLC, Austin, TX (US)

() Term: 15 Years

(21) Appl. No.: 29/808,554

(22) Filed: Sep. 21, 2021

Related U.S. Application Data

(63) Continuation of application No. 29/769,357, filed on Feb. 4, 2021, now Pat. No. Des. 933,428, which is a continuation of application No. 29/716,338, filed on Dec. 9, 2019, now Pat. No. Des. 909,819, which is a continuation of application No. 29/658,678, filed on Aug. 1, 2018, now Pat. No. Des. 871,159.
